DESIGN FOR AN AIR CONDITIONING UNIT OR SIMILAR ARTICLE

William Harold Sones, Twickenham, England, assignor to Electronaire Marketing Company Limited, London, England

Application March 19, 1938, Serial No. 75,970
In Great Britain February 21, 1938

Term of patent 3½ years

To all whom it may concern:

Be it known that I, William Harold Sones, a subject of the King of Great Britain and Northern Ireland, residing at 165 Powder Mill Lane, Twickenham, Middlesex, England, have invented a new, original, and ornamental Design for an Air Conditioning Unit or Similar Article, of which the following is a specification, reference being had to the accompanying drawing, forming part thereof, and in which:

Fig. 1 is a front perspective view of an air-conditioning unit embodying my new design; and

Fig. 2 is a rear perspective view thereof.

The design is also adapted for use as a vacuum cleaner, a hair drier, a clothes drier, a space heater, a deodorizer, a disinfecter or as a hot air thermal bath unit.

I claim:

The ornamental design for an air conditioning unit or similar article, substantially as shown and described.

WILLIAM HAROLD SONES.
